CLAIM

The ornamental design for slide position graph for an arrow rest, as shown and described.

DESCRIPTION

FIG. 1 is a top plan view of a slide position graph for an arrow rest, showing my new design;

FIG. 2 is a bottom plan view thereof;

FIG. 3 is a rear elevational view thereof;

FIG. 4 is a front elevational view thereof;

FIG. 5 is a left side elevational view thereof;

FIG. 6 is a right side elevational view thereof; and,

FIG. 7 is a perspective view thereof.

The broken line showing environment is for illustrative purposes only and forms no part of claimed design.

FIG. 3FIG. 4FIG. 2FIG. 6
